UNITED STATES PATENT OFFICE

ALFRED BRADSHAW, OF DRUMHELLER, ALBERTA, CANADA

LANDING GEAR FOR DIRIGIBLE AIRSHIPS

Application filed May 27, 1930. Serial No. 456,154.

This invention relates to a landing gear for dirigible airships, and has for one of its objects to provide a device of this character through the medium of which an airship may be anchored to the ground without the aid of a ground crew, through the medium of which the airship after being anchored may be brought down by its own crew to the level necessary to permit it to enter its hangar, and through the medium of which the airship after being lowered may be hauled by its own crew into the hangar.

The invention has for a further object to provide a device of the character stated through the medium of which the airship may be hauled from its hangar by its own crew and which shall be adapted to permit the crew after boarding the airship to release it for flight.

The invention has for a further object to provide a device of the character stated which shall be adapted to permit the airship, if desired, to be released for flight by a member of the crew left on the ground.

With the foregoing and other objects in view, the nature of which will appear as the description proceeds, the invention consists in the construction, combination and arrangement of parts hereinafter fully described and claimed, and illustrated in the accompanying drawings, wherein:—

Figure 1 is a view in side elevation of the landing gear with an airship anchored thereto and with the landing gear and airship in position to be hauled into a hangar;

Figure 2 is a top plan view of the landing gear with the anchors engaged therewith;

Figure 3 is a sectional view taken on a vertical plane extending longitudinally and centrally through the landing gear;

Figure 4 is a view partly in vertical section and partly in front elevation of the landing gear;

Figure 5 is a view partly in front elevation

and partly in vertical section of the body of the landing gear;

Figure 6 is a view partly in vertical section and partly in elevation illustrating a slightly modified form of the means for connecting the latch plates to the body;

Figure 7 is a view in front elevation illustrating a modified form of the means for closing the front end of the cable receiving slot of the anchor gear;

Figure 8 is a view partly in horizontal section and partly in top plan illustrating a modified form of the means for rotatably supporting the body of the landing gear upon its truck;

Figure 9 is a sectional view of the means shown in Figure 8;

Figure 10 is a view partly in vertical section and partly in side elevation of one form of the means for releasing the latch plates;

Figure 11 is a view in side elevation, and

Figure 12 is a view in top plan of a slightly modified form of the landing gear.

Referring in detail to the drawings, 1 designates a hangar, 2 a dirigible airship, and 3 the landing gear.

The landing gear 3 comprises a truck 4 which is mounted upon rails 5 for movement into and out of the hangar 1. The rails 5, which are laid with their upper sides in alignment with the surface of the ground and the floor of the hangar 1, are of channel formation in cross section and arranged with their open sides in opposed relation, and the wheels 6 of the truck 4 are arranged in the rails, so as to hold the truck against lateral and vertical displacement.

The truck 4 is provided at its center with a pedestal 7, and mounted upon the pedestal is a body 8 of elongated rectangular formation in plan. The body 8 is secured, as at 9, to the pedestal 7 for rotation about a vertical axis with respect to the truck 4. The body 8 comprises a bottom 10, sides 11, and a front end 12, and is fully open at its rear end.

The sides 11 are provided with outwardly directed lugs 13 which have their upper sides arranged in alinement with the upper edges of the sides 11. Latch plates 14 rest upon the upper edges of the sides 11 and upon the lugs 13, and are provided with lugs 15 through which and the lugs 13 bolts 16 extend to pivotally connect the latch plates to the body 8. The latch plates 14 are equal in length to the body 8, and extend across the upper side of the body with their inner longitudinal edges arranged in spaced relation to provide a slot 17 extending longitudinally of and communicating with the body. The slot 17 is adapted for the reception of cables 18 suspended from the airship 2 and provided at their lower ends with anchors 19 which, when the cables are in the slot, are arranged in the body 8 and contact with the lower sides of the latch plates 14. The front end of the slot 17 is closed by the front 12 of the body 8. The rear end of the body 8 and the rear end of the slot 17 are open to permit the cables 18 to enter the slot and the anchors 19 to enter the body. The rear end of the body 8 is formed to provide a flaring entrance 20 to the body and to the slot 17. The anchors 19 are preferably of spherical formation, and due thereto and to the flaring entrance 20, they and the cables 18 may be readily directed into the body 8 and slot 17. To prevent the cables 18 and the anchors 19 from being withdrawn from the rear end of the slot 17 and body 8, a latch 21 is employed. The latch 21 extends across the rear end of the slot 17, and is pivoted, as at 22, to one of the latch plates 14. The latch 21 is yieldingly held in active position across the slot 17 by a spring 23, and its movement under the influence of the spring is limited by a stop 24 carried by the latch plate 14 to which it is secured. The latch 21 extends in a forwardly inclined direction across the slot 17, and it moves forwardly into an inactive position under the pressure exerted thereon by the cables 18 while they are entering the slot. After the cables 18 have entered the slot 17, the latch 21 is returned to its active position by the spring 23, and it is held against any rearward movement from this position by the stop 24. As they are pivotally connected to the body 8, the latch plates 14 may occupy an active or inactive position. When they are in active position, the latch plates 14 extend horizontally across the upper side of the body 8 and prevent the withdrawal of the anchors 19 from the body. When they are in an inactive position, the latch plates 14 extend in an upwardly and inwardly inclined position with respect to the body 8 and permit the anchors 19 to be withdrawn from the body. The latch plates 14 are normally held in active position by levers 25 which are arranged outwardly of and at the sides of the body

8. The levers 25 are pivotally connected at their lower ends, as at 26, to the body 8, and have their upper or free ends arranged in engagement with the lower sides of those portions of the latch plates 14 that extend laterally beyond the body. 70

A plurality of the levers 25 are arranged at each side of the body 8, and the levers of each series are fixed to their pivot rod 26. A means is provided for holding the levers 25 in latch plate engaging position when it is desired to maintain the anchors 19 in engagement with the body 8 and for moving the levers into latch plate releasing position when it is desired to release the anchors. 75 80 This means comprises a vertical cylinder 27 fixed, as at 28, to the front end of the body 8, a piston 29 reciprocably mounted in the cylinder, a rod 30 fixed to the piston and extending through the upper end of the cylinder and having its upper end mounted in a guide 31 fixed to the front of the body, a spring 32 mounted on the rod between the guide and a collar 33 fixed to the rod, and links 34 pivoted to the collar and to the foremost of the levers 25. 90

The spring 32 normally maintains the piston 29 in the lower end of the cylinder 27, and it also normally maintains the links 34 in a position to hold the levers 25 in latch plate engaging position. One of the links 34 is extended to provide a lever 35 through the medium of which the links may be manually actuated to effect the movement of the levers 25 into latch plate releasing position. The lever 35 is used only when it is desired to effect the release of the airship 2 from the landing gear 3 by a member of the crew left on the ground. 100

A cartridge 36 of compressed gas is connected, as at 37, to the cylinder 27 at a point below the piston 29. The cartridge 36 is provided with a valve 38 which when open permits its gas to pass into the cylinder 27, with the result that the piston 29 will be moved upwardly and the levers 25 moved into latch plate releasing position. The valve 38 is adapted to be opened by a line extending therefrom to the airship 2. It will thus be seen that the cartridge 36 provides means through the medium of which the airship 2 may be released from the landing gear 3 by one of the crew in the airship. If desired, a cartridge of explosive powder may be used instead of the cartridge 36. The cartridge 40 of explosive powder will, when used, be connected to the cylinder 27, as at 41, and it will be provided with a detonator, not shown, adapted to be operated from the airship 2 through the medium of an electric cable 42. 110 120 125

The cables 18 extend from the bottom of the airship 2, and are connected to drums, not shown, carried by the airship. A cable 43 extends downwardly from the nose of the airship 2, and is provided at its lower end 130

with a spherical anchor 44. This cable, which is also connected to a drum, not shown, in the airship 2 is adapted to engage in a slot 45 formed in a standard 46 extending upwardly from a forwardly directed extension 47 of the bottom 10 of the body 8. The slot 45 is vertically arranged and opens out through the upper end of the standard 46, the front side of which is engaged by the anchor 44 when the cable 43 is in the slot. To facilitate the entrance of the cable 43 into the slot 45, the standard 46 is provided at its upper end with forwardly directed guide arms 48 which diverge forwardly from opposite sides of the upper end of the slot.

In practice, when it is desired to prepare for the landing of an airship, the landing gear 3 is moved to the desired place on the landing field with the body 8 heading into the wind. The body 8 is supported on the pedestal 7 by ball bearings 49 to permit it to rotate freely about its axis 9 and thus permit it to be maintained headed into the wind by the action of the wind against the outer sides of the flared entrance 20 to the body and slot 17. The airship approaches the landing gear 3 against the wind and with the cables 18 depending therefrom. As the airship moves over the landing gear 3, the anchors 19 are directed by the flared entrance 20 into the body 8 and the cables 18 are at the same time directed into the slot 17. When the front anchor 19 reaches the front end of the body 8, the airship assumes the position in which it is shown by dotted lines in Figure 1.

The cable 43 is now lowered to position it in front of the standard 46 between the guide arms 48. The motors of the airship are now slowed down, and the cables 18 are wound on their drums until the airship is lowered into the position in which it is shown by solid lines. While being lowered, the airship moves rearwardly with respect to the standard 46, and during this movement thereof, the cable 43 is carried into the slot 45, the cable being wound on its drum to carry the anchor 44 into engagement with the front side of the standard 46. The airship is now firmly anchored to the landing gear 3. After the body 8 has been turned upon the truck 4 to head it and the airship in the direction of the hangar 1, the truck is hauled along its rails 5 to convey the airship into the hangar.

When the airship is to start on a flight, it is hauled out onto the field. The airship may be released from the landing gear 3 by a person on the landing field pressing downwardly upon the lever 35. If desired, the airship may be released from the landing gear by one of its own crew through the medium of the cartridge 36 or 40, the former being adapted to be operated from aboard the airship through the medium of the line 39 and the latter being adapted to be operated from aboard the air-

ship through the medium of the electric cable 42.

If desired, the latch plates may be mounted upon the body 8 for sliding movement into anchor engaging or anchor releasing position, as shown in Figure 6. In this figure, the latch plates, here designated 14^a, are mounted in slides 50 carried by the upper edges of the sides 11 of the body 8. Means are employed for holding the latch plates 14 in anchor engaging position and for moving them into anchor releasing position. This means is similar to that shown in Figure 5 with the exception that the levers 25 are pivotally and slidably connected, as at 51, to the latch plates 14^a.

If desired, the front end of the slot 17 of the landing gear 3 may be closed by a manually operable stop 52 which may be withdrawn to permit the airship to drag the anchors from the front end of the body 8 as it is propelled away from the landing gear. When this stop, which is shown in Figure 7 is used, the latch plates may be fixed rigidly to the body 8. The landing gear does not require the use of two cables suspended from the bottom of the airship at opposite sides of its transverse center, in addition to the one suspended from the nose of the airship. If desired, the airship may be equipped with one cable suspended from its nose and one cable suspended from its transverse center, or it may be equipped with two cables suspended from its nose. The airship is shown in Figures 11 and 12 equipped with two cables suspended from its nose, one of the cables being designated 43^a and the other 43^b, and the anchors carried by the cables being designated 43^c and 43^d. The anchor 43^c is adapted to be engaged with the latch plates 14 and the anchor 43^d is adapted to be engaged with the standard 46. If desired, the part 46 may be arranged horizontally, as shown in these figures, such part being here designated 46^a and constituting a part of the extension 47 of the bottom 10. The anchor engaging element 46^a is provided with a slot 45^a for the reception of the cable 43 or 43^b, and it is formed to provide a flaring entrance 48^a for the slot. The provision of the airship with two cables suspended from its nose enables the airship to be anchored to the landing gear in the same manner that such ships are now anchored to a mooring mast, with the advantage of doing away with the expensive mooring mast. The use of these cables enables the landing gear to be considerably shortened, and also permits the anchoring of the airship to the landing gear during a storm.

If desired, the body 8 may be supported from the truck 4 by two or more wheels 53 attached to the body and running on a circular track 54 attached to the truck, as shown in Figure 9. The cylinder 37 is, as shown in Figure 5, provided above its horizontal center 130

with an opening 54 which permits the air above the piston 29 to escape from the cylinder during the upward movement of the piston to effect the retraction of the levers 25. 5 During its upward movement, the piston 29 passes beyond the opening 54 to permit the gas from the cartridge 36 or 40 to escape from the cylinder and thus enable the levers 25 to be returned to their active position by the 10 spring 32, the levers returning to such position after the anchor or anchors have been disengaged from the latch plates 14 and the latch plates have returned to their normal or active position. The latch plates 14 could be fixed 15 in a stationary manner to the body 8, the rear latch 21 could be omitted and the front end of the slot 17 could be closed by the front wall 12 of the body or by the retractile bolt 52.

While I have described the principle of the 20 invention, together with the structure which I now consider the preferred embodiment thereof, it is to be understood that the structure shown is merely illustrative and that such changes may be made, when desired, as fall 25 within the scope of the invention as claimed.

I claim:—

1. A landing gear for an airship, comprising a hollow body open at its rear end and provided in its upper side with a slot open 30 at its rear end, an anchor adapted to enter the body through the open end of the latter, a member adapted to suspend the anchor from the bottom of the airship and adapted to enter the slot as the anchor enters the body, a standard arranged forwardly beyond the body and provided with a vertical slot, a member adapted to be secured to the nose of the airship and adapted to enter the slot of the standard, and 35 an anchor carried by said last member and adapted to contact with the front side of the standard.

2. A landing gear for an airship, comprising a hollow body open at its rear end and provided in its upper side with a slot open 45 at its rear end, an anchor adapted to enter the body through the open end of the latter, a member adapted to suspend the anchor from the bottom of the airship and adapted to enter the slot as the anchor enters the body, a standard arranged forwardly beyond the body and provided with a vertical slot, a member adapted to be secured to the nose of the airship and adapted to enter the slot of the standard, an anchor carried by said last member 50 and adapted to contact with the front side of the standard, and arms extending in forwardly divergent relation from the standard and at opposite sides of the upper end of the slot therein, said arms being adapted to guide 55 said last member into said slot.

3. A landing gear for an airship, comprising a body, anchor engaging elements pivoted to the body for movement into active or inactive position, pivoted levers engaging 60 said elements to hold them in active position,

means holding the levers against accidental movement out of engagement with said elements, and means by which the levers may be moved out of engagement with said elements to permit the latter to be moved into inactive 70 position.

4. A landing gear for an airship, comprising a body, anchor engaging elements pivoted to the body for movement into active or inactive position, pivoted levers engaging said 75 elements to hold them in active position, means holding the levers against accidental movement out of engagement with said elements, and means associated with said first means and adapted to be operated to move the levers out of engagement with said elements to permit the latter to be moved into inactive position.

5. A landing gear for an airship, comprising a body, anchor engaging elements pivoted to the body for movement into active or inactive position, pivoted levers engaging said elements to hold them in active position, means holding the levers against accidental movement out of engagement with 80 said elements, a cylinder, a piston mounted in the cylinder, links connected to the piston and levers, means yieldably holding the links in position to prevent the levers from accidentally moving out of engagement with said 85 elements, and a cartridge connected to the cylinder and adapted to be controlled to permit a piston operating medium to be directed therefrom into the cylinder, the operation of the piston by said medium being adapted to effect the movement of the levers out of engagement with said elements to permit the latter to be moved into inactive position.

6. A landing gear for an airship, comprising a truck, a body rotatably mounted on the truck, anchor engaging elements mounted on the body and extending from the front to the rear end thereof and arranged to provide therebetween a slot, and elements extending laterally and rearwardly from the rear end of the body and adapted to be engaged by the wind to maintain the body headed into the wind.

7. A landing gear for an airship, comprising a truck, a hollow body open at its rear end and provided with a flaring entrance for said end, latch plates arranged at the upper side of the body and spaced to provide therebetween a slot communicating at its rear end with said entrance, means pivotally connecting the latch plates to the body, means carried by the body and releasably engaging the latch plates to hold them against pivotal movement, and means by which said second means may be moved out of engagement with 115 the latch plates.

8. A landing gear for an airship, comprising a truck, a hollow body open at its rear end and provided with a flaring entrance for said end, latch plates arranged at 120

130

the upper side of the body and spaced to provide therebetween a slot communicating at its rear end with said entrance, means pivotally connecting the latch plates to the body, means carried by the body and releasably engaging the latch plates to hold them against pivotal movement, means by which said second means may be moved out of engagement with the latch plates, a member extending forwardly from the body, a standard at the front end of said member and provided with a vertical slot open at its upper end, and guide arms extending in forwardly divergent relation from the standard at opposite sides of the upper ends of the slots.

9. A landing gear for an airship, comprising anchor engaging elements arranged to provide therebetween a slot open at one end, and a retractable member extending across the other end of the slot.

10. A landing gear for an airship, comprising anchor engaging elements arranged to provide therebetween a slot, a latch extending across the slot near one end thereof, and a retractable member extending across the other end of the slot.

11. A landing gear for an airship, comprising anchor engaging elements arranged to provide therebetween a slot open at its rear end, and another anchor engaging element located below and forwardly of said first elements and provided with a slot open at its front end.

12. A landing gear for an airship, comprising a truck, anchor engaging elements mounted on the truck and arranged to provide therebetween a slot open at one end, means rotatably mounting the anchor engaging elements on the truck, and means adapted to be engaged by the wind to maintain the anchoring elements in position on the truck to present the opened end of said slot to the wind.

13. A landing gear for an airship, comprising anchor engaging elements of elongated formation and arranged to provide therebetween a slot extending longitudinally thereof and open at one end, means supporting said elements for relative movement into active or inactive position, and means releasably holding said elements in active position.

14. A landing gear for an airship, comprising anchor engaging elements of elongated formation and arranged to provide therebetween a slot extending longitudinally thereof and open at one end, means supporting said elements for relative movement into active or inactive position, means releasably holding said elements in active position, and means by which said second means may be actuated to effect the release of said elements.

15. A landing gear for an airship, comprising a rotatably mounted body, a member extending forwardly from the body and provided with an anchor receiving slot having a forwardly diverging entrance, and means car-

ried by the body for engagement by the wind to maintain the body in position to present the entrance of said slot to the wind.

16. A landing gear for an airship, comprising anchor engaging elements arranged to provide therebetween a slot open at its rear end, an another anchor engaging element located forwardly of said first elements and provided with a slot open at its front end.

In testimony whereof I hereunto affix my signature.

ALFRED BRADSHAW.
